(57) **CLAIM**

The ornamental design for a kickstand plate, as shown and described.

DESCRIPTION

FIG. 1 is a perspective view of a first embodiment of my new design for a kickstand plate;

FIG. 2 is a top plan view;

FIG. 3 is a left side view;

FIG. 4 is a right side view;

FIG. 5 is a rear elevational view;

FIG. 6 is a front elevational view; and

FIG. 7 is a bottom plan view of a first embodiment.

FIG. 8 is a perspective view of a second embodiment of my new design for a kickstand plate;

FIG. 9 is a top plan view;

FIG. 10 is a right side view;

FIG. 11 is a left side view;

FIG. 12 is a rear elevational view;

FIG. 13 is a front elevational view; and,

FIG. 14 is a bottom plan view of a second embodiment.

The second embodiment shown in FIGS. 8-14 has a non-slip material forming the top flat surface of the kickstand plate. Features shown in dashed lines form no part of the design to be patented.
